Attorneys

UNITED STATES PATENT OFFICE

THOMAS G. MOULDING, OF FLINT, MICHIGAN, ASSIGNOR TO A C SPARK PLUG COMPANY,
OF FLINT, MICHIGAN, A COMPANY OF MICHIGAN

TEMPERATURE INDICATOR

Application filed June 23, 1928. Serial No. 287,737.

This invention relates to an improved bulb for temperature indicating instruments, and has particular reference to the type of instruments used on internal combustion engines of automotive vehicles.

In the conventional form these instruments consist of a suitable pressure gage connected by means of tubing to a bulb adapted to contain a temperature responsive fluid. The bulb is exposed to the heat of the body the temperature of which is to be measured and the resultant expansion of the fluid in the bulb exerts a pressure on a gage through interconnecting tubing. This gage is calibrated so that it will serve to indicate the temperature of the medium in which the bulb is immersed.

It is the object of the present invention to make a bulb which is less subject to leaks than the types now in use. These leaks may be caused by excessive vibration, such as in the case of high speed internal combustion engines, or by the pressure built up in the tube when in use.

I accomplish the object of the invention by a novel method of attaching the tubing to the bulb, and in practice I prefer to use tight fitting and subsequently soldered joints at the ends. In the preferred form the tubing 30 extends completely through the bulb with a projecting closed tip at the free end. A portion of the tube wall is cut away within the bulb so that the fluid may exert a pressure in the tubing and so that the fluid may be injected into the bulb in manufacture. It is clear that with the tube extending completely through the bulb a more rigid connection can be made and one that will not become loose due to vibration.

Tighter soldered joints are made possible in the preferred form, by the novel shape of the bulb at the free end, and by the novel relation between the bulb and the bushing at the jam nut end.

At the free end the bulb is bent so as to re-enter the open end, and when the tube is inserted the curved end thus formed provides a pocket for solder. At the jam nut end the bulb, bushing and tube form another pocket for solder.

A modified form of jam nut end consists in having the bulb projecting entirely through the bushing and being spun over at the end, thus providing a pocket for solder and making it necessary to unite only two surfaces instead of four.

In a modified form the tubing does not extend completely through the bulb but terminates about midway. An orificed plug is pressed into the bulb and against a bead near the open end and is soldered in place. After the tube has been filled the orifice is plugged up with a suitable pin.

In the drawings:

Figure 1 shows a section through the improved bulb, with the tube and all joints sealed, and with strengthening wire wound about the tube.

Figure 2 is a side view of the assembled bulb and tubing with the jam nut applied.

Figure 3 shows a typical bulb installation and the method of attaching the tube to a suitable pressure gage.

Figure 4 shows a modified form of bulb and means for attaching to a bushing.

Figure 5 is a view of another modification.

Referring to the drawings, the numeral 10 indicates the bulb which is generally of cylindrical form and has open ends, and is filled with a suitable heat responsive liquid. The free end 12 of the bulb has its edges rebent or inturned as shown at 14, and spaced from the walls of the bulb 10 as shown at 16.

The opposite end of the bulb is swaged or reduced in diameter as shown at 18 and 85 surrounding this reduced or swaged portion is a bushing 20, the inner surface of which substantially conforms to the surface of the swaged portion. This swaged portion has a tapered part shown at 22. If desired, the tube end may be left straight and a bushing or collar inserted between the bulb and tube.

The swaged end 18 does not extend entirely through the bushing, but slightly short thereof, as shown at 24. This will leave a small pocket 25 at the end of the bulb with the bushing forming the walls.

Extending entirely through the bulb 10 is a slender tube 26 having the bore 28 and a cut out portion 30 within the bulb 10 to al-

low the expansive fluid to have access to the bore 28. This structure allows for a ready filling of the bulb. The free end 32 of the tube 26 extends outwardly of the bulb 10 and after filling the latter the end is preferably closed as shown at 34 by pinching or pressing the walls of the tube together and thereby forming a liquid tight connection. If desired, a plug or other suitable closure 10 for the tube end may be used. From the structure as described it will be seen that the pressure tending to force the tube out of the bulb is equal in both directions. The two forces are therefore resisted by the tensile 15 strength of the tube as well as by the strength of the soldered joints.

The tube 26 forms a relatively close fit with the rebent portion 14 of the bulb 10 and in order to make a liquid tight seal, solder 20 shown at 36 is poured into the pocket 38 formed between the rebent portion and the tube 26. This solder will form a liquid tight joint due to its molecular adherence to the metal surfaces of the tube 26 and the bulb 25 10.

If desired, the end 12 may be left straight and reduced by swaging, as is shown at 18 at the opposite end of the tube, thereby eliminating the rebent portion. This swaged end 30 may have a somewhat flared or conical mouth portion to form a pocket adjacent the tip end of the tube and by filling this pocket with solder a liquid tight joint is obtained. The tip 32 will project from the bulb end as 35 shown in Figure 1.

The opposite or swaged end of the bulb is also filled with solder in order to form a liquid tight connection. This solder fills the pocket 25 formed between the space above 40 the swaged end of the bulb 10 and the outer plane of the bushing 20. In case there should be any space between the bulb 10 and the bushing 20, the solder will flow thereinto as shown at 40 in Figure 1. The swaged end 18 45 forms a very close contact with the tube 26, however, should there be any slight space between the two, the solder will also flow thereinto and due to the molecular adherence will form a very intimate and liquid tight 50 connection.

The bulb may be applied to any suitable container as shown in Figure 3. For purposes of illustration, I have used the cooling system of an internal combustion engine, the piping of which is shown at 42. To this piping there is applied the boss 44, and in the opening of this boss there is received the threaded portion 46 of a jam nut 48. The jam nut has a bore for the reception of the tubing 26 and the inner or threaded end thereof abuts against a shoulder 50 on the bushing 20. The bushing 20 has a further shoulder 52 which rests on a corresponding shoulder 54 in the boss 44, and when the 55 jam nut 48 is screwed home, it will hold the

bulb 10 in liquid tight relation in the piping 42 of the cooling system.

The tubing 26 is preferably armored as shown at 56 in order to provide a protecting covering.

The tube 26 leads to a gage 58 secured by means of the bolt and nut 60 at any suitable point. In actual practice, this gage is fastened at the instrument board of an automotive vehicle, and is therefore adapted for reading at a distance on the bulb.

As a modification of the structure of Figure 1, I use the construction shown in Figure 4. In this species the tube 10' has its free end open and is closed by means of a plug 62 20 having a central opening 64. The plug rests against a bead 66 pressed in the bulb side and is secured in position preferably by soldering, while a suitably tapered pin 68 closes the opening 64 in the plug 62. The purpose of 25 the opening is to allow the insertion of a suitable expansive fluid.

The tube 26' of this species does not extend entirely through the bulb 10', but is considerably short of its inner end as shown at 30 70 in Figure 4.

The opposite end of the bulb 10' has a swaged portion 18' similar to that shown in Figure 1, except that it extends entirely through the bushing 20, and has its end spun 35 or turned over as shown at 72 to overlap the outer surface of the bushing 20 and thereby hold it in place. This spun over portion will form a small pocket 74 adjacent the tube 26' 40 which may be filled with solder in order to form a liquid tight connection. This arrangement leaves but the surfaces between the swaged end and the tube 10' to be closed 45 eliminating the surfaces between the swaged end 18' and the bushing 20.

The spaces 76 within the bulbs 10 or 10' is filled with a suitable liquid which is readily responsive to changes in heat and whose expansion will be registered through the intermediary of the tube 26 on the gage 58.

By referring to the structure of Figure 1 it will be seen that due to the fact that the tube 26 extends entirely through the bulb 10, a more rigid and intimate connection with the bulb is attained, and as no free end is exposed there will be no tendency for the liquid to press thereagainst and in this way interfere with the accurate working of the bulb. Moreover, due to the space 16 between the inturned end 14 and wall of the bulb 10, the pressure exerted by the liquid within the bulb will tend to press the bent over end 14 115 tighter against the tube 26.

Referring to the modified structure of Figure 5 it will be seen that the bulb 10 has its end 12' reduced and left straight as at 14'. This structure will facilitate the mounting 120 of the tube 26 and is cheaper to manufacture. The end has a soldered liquid tight joint 36 125 between the tube 26 and the bulb 10.

I claim:

1. In a heat responsive instrument, a bulb adapted to contain a heat sensitive fluid and having one end portion turned on itself, and a tube passing through said end and bulb and having an opening communicating with the interior of said bulb. 5
2. In a heat responsive instrument, a bulb having one end inturned and spaced from the walls of the bulb, said end having a opening, a tube passing through said opening, and a liquid tight joint between said tube and inturned end. 10
3. In a heat responsive instrument, a bulb open at both ends, a tube passing through said bulb, a reentrant end to said bulb contacting with said tube, a liquid tight solder seal at said reentrant end, a bushing surrounding the opposite end, said bulb having a reduced end 20 at said bushing extending short of the outer plane thereof, and a liquid tight solder seal filling the space between said tube, bushing and bulb.
4. In a temperature responsive instrument of the class described, an elongated bulb having openings at its ends, a slender tube extending through said bulb at its openings and having one end seated, means fastening the ends of said bulb to said tube, a portion of 25 said tube within said bulb being cut away.
5. In a temperature responsive instrument of the class described, a bulb having a free end and a jam nut end, a slender tube fastened in said bulb and having an opening communicating with the interior of the bulb, a bushing surrounding the jam nut end of said bulb, there being a pocket at said jam nut end, a material in said pocket to join said tube and bulb molecularly, and means to 30 seal the free end of said bulb.
6. In a temperature responsive instrument of the class described, a bulb having a free end and a jam nut end, a slender tube extending completely through said bulb and having one end sealed, means to fasten said bulb to said tube at the jam nut end, a reentrant surface on said free end, a pocket formed by said surface and said tube, a material in said 35 pocket to join said tube and bulb molecularly, and a cut away portion on said tube within said bulb.
7. In a heat responsive instrument having a bulb, a bushing, a reduced end on said bulb extending into said bushing, said end extending short of the outer plane of the bushing, and a solder seal between said bushing and end. 45
8. In a device of the class described, a bulb adapted to contain a heat sensitive fluid and having its ends reduced and left straight, a tube in said bulb having an opening communicating with the interior thereof and passing through said reduced ends, and a liquid tight joint between said tube and bulb. 50
9. In a heat responsive instrument, a bulb 65

adapted to contain a heat sensitive fluid and having a reentrant end, a bushing at the other end, and a tube passing through both said ends and said bulb and having an opening communicating with the interior of said bulb, 70 said tube being closed at one end.

10. In a heat responsive instrument, a bulb adapted to receive a heat sensitive fluid and having one end portion turned on itself, a tube passing through said end and entirely 75 through said bulb, said tube having an opening communicating with the interior of said bulb, and a liquid tight joint between said turned over portion and said tube.

11. In a heat responsive instrument, a bulb 80 adapted to receive a heat sensitive fluid and having one end portion turned on itself and spaced from the walls thereof, and a tube passing through said end and entirely through said bulb, said tube having an opening communicating with the interior of said bulb. 85

12. In a heat responsive instrument, a bulb adapted to receive a heat sensitive fluid and having one end portion turned on itself, a tube passing through said end and bulb and having an opening communicating with the interior of said bulb, said turned end forming 90 a recess adjacent the tube, and a soldered joint formed at said recess.

In testimony whereof I affix my signature. 95
